UNITED STATES PATENT OFFICE.

PIERPONT E. DUTCHER, OF UPPER MONTCLAIR, NEW JERSEY.

EXCAVATING APPARATUS.

1,383,913.

Specification of Letters Patent.

Patented July 5, 1921.

Application filed November 28, 1919. Serial No. 341,035.

To all whom it may concern:

Be it known that I, PIERPONT E. DUTCHER, a citizen of the United States, and resident of Upper Montclair, in the county of Essex and State of New Jersey, have invented a new and useful Improvement in Excavating Apparatus, of which the following is a specification.

This invention relates to an excavating apparatus and has for its object to provide an apparatus having a bucket which may be controlled and operated by means of lines manipulated from one side of the place desired to be excavated and between predetermined points.

Another object is to provide means operated at the side of the excavation for controlling the position and movement of the bucket.

20 A still further object is to provide certain improvements in the form, construction and arrangement of the parts, whereby the above named and other objects may be effectively attained.

25 A practical embodiment of my invention is represented in the accompanying drawings, in which—

30 Figure 1 represents in plan a view of my improved apparatus showing the bucket, the lines attached thereto, the means by which the lines are controlled and operated and the means for supporting and guiding the lines and bucket.

35 Fig. 2 represents in side elevation, on an enlarged scale, a bucket, its lines and mechanism carried by the bucket in the position it will assume while being dragged with its load, also showing in dotted outlines, the position the mechanism will assume when the 40 bucket is being hauled back.

45 Fig. 3 represents a longitudinal central section of the bucket, with its lines and mechanism in a position for digging.

Fig. 4 represents a side elevation of the 50 bucket in the position it will assume when dumping.

55 Fig. 5 represents a plan view, on a still larger scale, of the bucket actuating mechanism, and a portion of the lines connected thereto.

Fig. 6 represents a side elevation of the same.

Fig. 7 represents a similar view with the parts in another position.

55 Fig. 8 represents a similar view with the parts in still another position.

Fig. 9 represents a vertical section taken in the plane of the line IX—IX of Fig. 7, looking in the direction of the arrows, and

Fig. 10 represents a vertical section taken 60 in the plane of the line X—X of Fig. 8, looking in the direction of the arrows.

To set up the apparatus at the place to be excavated, I provide anchorages denoted by 1, 2 at one side and an engine 3 having two 65 winding drums 4, 5 at the other side of the proposed excavation. The engine 3 may be of any well known and approved type having means by which the two drums may be controlled and operated. Between the 70 anchorages 1, 2 there is stretched a line 6 upon which a guide pulley block 7 is supported and arranged to travel. This pulley block 7 is held in its position on the line 6 by means of a rope 8, one end of which is 75 permanently attached at 9 to the pulley block, and the free end removably secured to the anchorage 2.

A bucket 10 is provided with a drag line 11 and a haul-back line 12. The drag line 80 11 is arranged to be carried forwardly and wound directly on the drum 4 of the engine, while the haul-back line 12 is carried rearwardly through the pulley block 7, pulley 13 on the anchorage 1 and thence forwardly 85 through supporting pulleys 14 mounted on poles 15 and around a guide 16 to the drum 5. It will, of course, be understood that the drums 4, 5 may be so connected that they may be driven either together or separately, 90 so that one line may be tightened and the other slackened or both tightened or slackened as the case may require.

The drag line 11 is connected with a digging bail 17, the ends of which are secured 95 to ears 18 on the bucket. The haul-back line 12 is connected to the bucket by a compensating line 19, one end of which is permanently secured to the bucket at 20 and the other end developed into a bail 21, the ends of 100 which are fastened to the front end of the bucket at 22. This bail 21 is provided with a spreader 23 to prevent it from chafing on the bucket. The compensating line 19 passes from the bail 21 around a pulley 24 in the 105 end of the haul back-line 12, forwardly to a pulley 25 carried by a bracket 26 extending rearwardly from an actuating mechanism, to be hereinafter described, thence rearwardly and secured to the bucket at 20.

110 The actuating mechanism comprises a carriage 28, a pair of latches 29 fixed on a

pin 30, journaled in the carriage and connected by a bridge 31 which is secured to the latches by screws 32. The latches are arranged upon opposite sides of the carriage 5 and normally rest in recesses 33 in the sides of the carriage.

A curved I-beam 34 is arranged on the bucket in position to form a track upon which the carriage 28 is held in slidable engagement by means of inwardly disposed fingers 35 which engage the upper flanges 36 of the beam.

Stops 37 are fixed upon opposite sides of the I-beam 34 so as to be engaged by the latches 29 when at rest in the recesses 33, as shown in Figs. 3, 7 and 9. The latches are lifted out of the path of the stops 37 by means of a cam 38 mounted on a shaft 39 journaled in the carriage 28, which shaft and cam are arranged to be rotated by a trigger 40 pivoted on a bracket 41 fast on the I-beam, which trigger is adapted to operatively engage each tooth 42 of a star wheel 43 pinned on one end of the shaft 39 when the carriage 28 moves to the left, Fig. 8. As the shaft 39 with its cam 38 is rotated, the cam will be caused to pass through a hole 44 in the carriage and engage the bridge 31 and so actuate the latches. The teeth on the star wheel are so disposed that each time the trigger moves a tooth, the shaft 39 will be rotated a quarter of a revolution, and the shape of the cam is such that the latches will be raised and lowered alternately with each movement of the carriage in the same direction or, in other words, will be raised on each second movement of the carriage to the left, Fig. 8. When the carriage 28 moves to the right, Figs. 2 and 3, the star wheel 40 will strike the trigger and swing it on its pivot so as to permit the carriage to pass, the weighted end 45 on the trigger serving to return it to its normal position.

The carriage 28 is controlled and operated in certain of its movements by the drag line 11 through a connection 46 which is attached to an eye 47 projecting from the carriage.

In operation, assuming that the anchorages, engine, lines and bucket have been set up in the position shown in Fig. 1, and the apparatus ready to be operated, the bucket is hauled back to a place where it is desired to start the excavation. In hauling back the bucket, the engine is caused to wind the line 12 on the drum 5 and the drum 4 permitted to unwind, which leaves the line 11 slack. The tension on the line 12, to haul the bucket rearwardly is imparted through the pulley 24 to the compensating line 19, pulley 25 of the carriage 28 and the bail 21. The position the carriage 28 will assume on the curved I-beam is shown in dotted lines in Fig. 2. When the bucket has been hauled back to the desired place and is ready to be

brought to a digging position, the drum 4 is rotated to wind the line 11, while the drum 5 is allowed to unwind to slacken the line 12. In tightening the line 11, the connection 46 will cause the carriage 28 to travel forwardly on the track, in which movement, one of the teeth 42 of the star wheel 43 will engage the trigger 40, which in turn will rock the shaft 39 so that the cam 38 will allow the latches to rest in the recesses 33 of the carriage, thereby placing the latches in position to be operatively engaged by the stops 37, and hold the carriage in position on the track. As the tension on the drag line 11, digging bail 17 and connection 46, is continued, and the haul-back line 12 slackened, the bucket will be caused to tilt forwardly to the digging position, shown in Fig. 3, in which position the line 11, digging bail 17 and connection 46 hold the bucket throughout the digging operation. When the digging operation has been completed and it is desired to haul the contents of the bucket toward the side of the excavation, the drag line 11 is slackened and the haul-back line 12 tightened sufficiently to draw the carriage rearwardly on the track so that the star wheel 43 will again pass over trigger 40, whereupon the drag line 11 is tightened and the haul-back line 12 slackened so that the carriage will return over the trigger 40 and set the cam 38 so that the latches will be lifted to clear the stops 37, and the carriage allowed to assume a position on the track, as clearly shown in Fig. 2. In this position, the load may be dragged to the side of the excavation and there dumped. To dump the contents of the bucket, the line 11 is permitted to slacken and the drum 5 is rotated to wind the line 12 thereon, thus sliding the carriage rearwardly until it has just passed the crest of the I-beam 34. With the parts in this position, tension is exerted on the line 11 and the connection 46 tips the bucket up into dumping positions. As the bucket starts to tip over its digging edge, the line 12 is allowed to slip a little by slightly releasing the brake on the drum 5. After the contents of the bucket have been dumped, the line 11 may be slackened and the bucket allowed to return, by gravity, to the haul-back position with the carriage in the position shown in dotted lines in Fig. 2 when the bucket may be hauled back by the line 12 and the cycle of operations repeated as above described.

It is to be emphasized that the advantages obtained by this apparatus are distinctive in that the bucket used picks up its load and carries it to a place to be dumped; that the bucket is not suspended or carried; that the manipulation of the bucket is controlled and operated entirely from the side of the excavation, by alternating tension on the digging and haul-back lines without

- placing tension on the opposing line, thereby materially saving wear and tear on the apparatus, due to opposite forces being applied to the lines; that the bucket will assume 5 digging, carrying and haul-back positions with operating tension applied to one line at a time; and that the dumping position only is assumed with the tension applied to both lines.
- 10 It is obvious that various changes may be resorted to in the form, construction and arrangement of the several parts and in the method of operation without departing from the spirit and scope of my invention; 15 and hence I do not wish to be limited to the details herein shown and described except as they may be set forth in the claims.
- What I claim is:
1. An excavating apparatus including, a bucket adapted to operate on the ground, a line circuit secured to said bucket, means for actuating the line circuit to cause the bucket to dig and then carry its load, and means for causing the bucket to maintain a 25 regular digging angle with tension on the drag line only irrespective of the amount of load in the bucket.
  2. An excavating apparatus including, a bucket adapted to operate on the ground, a line circuit secured to said bucket, means for actuating the line circuit to cause the bucket to dig, carry its load and to dump the load, and means for causing the bucket to maintain a regular digging angle with 30 tension on the drag line only irrespective of the amount of load in the bucket.
  3. An excavating apparatus including, a bucket adapted to operate on the ground, a line circuit secured to said bucket, means 40 for actuating the line circuit to cause the bucket to dig, carry its load, dump the load, and to haul back, and means for causing the bucket to maintain a regular digging angle with tension on the drag line only irrespective of the amount of load in the bucket.
  4. An excavating apparatus including, a bucket having a drag line and a haul-back line, means slidably mounted on said bucket 50 and connecting said drag and haul-back lines, and means for operating the drag and haul-back lines to move said slidable means for controlling the position and movement of the bucket.
  5. An excavating apparatus including, a bucket having a drag line and a haul-back line, means slidably mounted on said bucket and connecting said drag and haul-back lines, means fast on the bucket adapted to 60 engage said slidable means for holding it in a fixed relative position, and means for operating the drag and haul-back lines to move said slidable means for controlling the position and movement of the bucket.
  6. An excavating apparatus including, a bucket having a drag line and a haul-back line, means slidably mounted on said bucket and connecting said drag and haul-back lines, a stop on the bucket, a latch carried by said slidable means in position to engage 70 said stop to hold the means in a fixed relative position, and means for operating the drag and haul-back lines to move the slidable means for controlling the position and movement of the bucket.
  7. An excavating apparatus including, a bucket having a drag line and a haul-back line, means slidably mounted on said bucket and connecting said drag and haul-back lines, a stop on the bucket, a latch carried by said slidable means in position to engage 75 said stop to hold the means in a fixed relative position, means for moving said latch to throw it out of contact with the stop, and means for operating the drag and haul-back lines to move the slidable means for controlling the position and movement of the bucket.
  8. An excavating apparatus including, a bucket having a drag line and a haul-back line, means slidably mounted on said bucket and connecting said drag and haul-back lines, a stop on the bucket, a latch carried by said slidable means in position to engage 80 said stop to hold the means in a fixed relative position, means for moving said latch to throw it out of contact with the stop, and means for operating the drag and haul-back lines to move the slidable means for controlling the position and movement of the bucket.
  9. An excavating apparatus including, a bucket having a bottom, a drag and a haul-back line connected to said bucket, and means for operating said lines so as to cause the bucket to assume a digging or load carrying position while permitting slackness 90 in the haul-back line.
  10. An excavating apparatus including, a bucket having a bottom, a drag and a haul-back line connected to said bucket, and means for operating said lines so as to cause the bucket to assume digging, carrying, and haul-back positions with tension on only one of said lines at a time.
  11. An excavating apparatus including, a bucket having a bottom, a drag and a haul-back line connected to said bucket, and means for operating said lines so as to cause the bucket to assume digging, carrying, haul-back positions with tension on only one of said lines at a time, and to assume a haul-back position without tension on the drag 100 line.
- In testimony that I claim the foregoing as my invention I have signed my name this twenty-fifth day of November 1919.
- PIERPONT E. DUTCHER.
